UNITED STATES PATENT OFFICE.

ROY P. M. DAVIS, OF MOUNT UNION, PENNSYLVANIA.

APPARATUS AND METHOD FOR SANDING BRICK MOLDS.

Application filed October 5, 1923. Serial No. 666,805.

To all whom it may concern:

Be it known that ROY P. M. DAVIS, a citizen of the United States of America, residing at Mount Union, in the county of 5 Huntingdon and State of Pennsylvania, has invented certain new and useful Improvements in Apparatus and Methods for Sanding Brick Molds, of which the following is a specification.

10 My invention relates to apparatus and method for sanding brick molds and more particularly for sanding the plate which forms the bottom of the molds.

It is well known among brick makers that 15 the mud or material from which bricks are made will adhere to the mold and bottom plate therefor. This adhering brick interferes with the making of a perfect brick and it is the object of the present device 20 to obviate this objectionable condition by sanding the mold and mold plate prior to the introduction of the charge of mud into the mold.

In the accompanying drawings:

25 Figure 1 is a plan view of an apparatus illustrating a preferred embodiment of my invention;

30 Figure 2 is an enlarged detail sectional view of the sand receptacle or trap and the air nozzle therefor, the air supply being cut off; and

35 Figure 3 is a side elevation partly broken away of the mud feeding chute of a brick making machine showing the sand receptacle and air nozzle attached thereto, a slicker and mold plate being also shown and the air supply being open.

40 Referring more particularly to the drawings, 5, denotes the open ended enclosure or chute of a brick making machine (not shown) through which mud or other material is precipitated to the brick mold (not shown).

45 Secured to the side wall 6, of the chute by any suitable fastening means (not shown) is a threaded collar 7, internally threaded to receive the inner threaded end of a pipe 8, the outer end of which is connected to the inner threaded end of a T coupling member or pipe 9. A nozzle 10, projects 50 through the outer end of the member 9, and is threadedly connected thereto by means of the threaded head or cap 11, forming a part of the nozzle. This head or cap 55 11, is apertured as at 12, to receive the outlet end of an air blast pipe 13, leading

from any suitable source of compressed air supply (not shown). A two way valve 18, in the pipe is operated by means of the handle 19, for controlling the supply of 60 compressed air.

A bin or hopper 14, adapted to contain a quantity of sand 15, communicates with the member 9, by means of a pipe 16, the latter being connected at its upper end to the inclined bottom of the hopper and at its lower end to the vertically disposed neck 17, of the member 9.

From the foregoing it is thought the 70 operation of the apparatus will be apparent, but a brief description thereof will be given as follows: Upon the arrival of the mold (not shown) and the bottom plate 20, therefore, at the filling station or position beneath the mud chute 5, (see Figure 3) valve 18, is opened allowing the compressed air to escape from nozzle 10, carrying with it sand in the form of a spray 21, which falls upon and thoroughly sprinkles the mold plate 20. 75 As the sand is carried away from the receptacle it is automatically replaced by a fresh supply from the bin or hopper 14.

The combined length of the pipe 8, and coupling 9, is approximately double the 80 length of the nozzle 10, the latter projecting slightly beyond the top opening of the coupling with which the pipe 16, communicates.

Consequently when the valve 18, is closed, the sand in the coupling becomes chocked 85 and automatically cuts off the flow of sand from the bin or hopper 14. It will also be noted that the pipe 8, and coupling 9, form in effect, a sand receptacle 22. When the air supply is shut off the accumulation of 90 sand in the pipe 8, and coupling 9, covers and flows beyond the end of the nozzle thus providing a charge of sand in front of the nozzle. A new supply of sand constantly drops down by gravity in front of the nozzle 95 as fast as the sand is forced through the pipe 8, into the chute 5, and the nozzle therefore always has a uniform charge of sand to work upon. In Figure 3, a slicker 100 25, is illustrated merely to show the relative position of my invention with respect to the parts of a brick making machine.

105 While the mold is illustrated as being sanded while stationary beneath the mud chute, it will of course be understood that the sanding operation may be performed 110 while the plate is in transit. Also that a plurality of nozzles 10, may be employed.

Having thus described my invention:
What I claim is:

1. The herein described method of sanding mold plates, which consists in introducing sand in the form of a spray into a confined space above the plate so that the spray will fall by gravity upon the plate.
2. The herein described method of sanding mold plates which consists in forcing sand into an open ended enclosure positioned above the mold plate by means of an air blast.
3. An apparatus for sanding mold plates comprising a sand receptacle having a horizontally disposed air nozzle therein, and a

sand inlet opening, above said nozzle, means for feeding a supply of air through said nozzle, means for feeding sand to said receptacle, an open ended enclosure with which said sand receptacle communicates, whereby sand forced into said enclosure will drop by gravity through said enclosure upon the mold plate to be sanded. 20

In testimony whereof I affix my signature in presence of two witnesses.

ROY P. M. DAVIS.

Witnesses:

V. L. WALLETT,
ERMA ROSENSTEEL.
